PACK RACK

Henry L. Harvill, Corona, Calif.

Application January 21, 1954, Serial No. 28,616

Term of patent 14 years

(Cl. D87—5)

To all whom it may concern:

Be it known that I, Henry L. Harvill, a citizen of the United States of America, residing at Corona, in the county of Riverside and State of California, have invented a new, original, and ornamental Design for Pack Rack, of which the following is a specification, reference being had to the accompanying drawings, forming a part thereof.

Fig. 1 is a front elevational view of a pack rack, showing my new design;

Fig. 2 is a side elevational view thereof; and

Fig. 3 is an enlarged transverse sectional view thereof, taken through 3—3 of Fig. 1.

I claim:

The ornamental design for a pack rack, as shown.
